UNITED STATES PATENT OFFICE

129,970

DESIGN FOR AN AIRPLANE

Michael J. Wenzow, Chicago, Ill.

Application April 3, 1941, Serial No. 160,120

Term of patent 7 years

To all whom it may concern:

Be it known that I, Michael J. Wenzow, a citizen of the United States, residing at Chicago, in the county of Cook and State of Illinois, have invented a new, original, and ornamental Design for Airplanes, of which the following is a specification, reference being had to the accompanying drawings, forming a part thereof:

Fig. 1 is a top plan view of an airplane, showing my new design;

Fig. 2 is a side elevational view thereof; and
Fig. 3 is a front elevational view.

I claim:

The ornamental design for an airplane, as shown.

MICHAEL J. WENZOW.
